AIR CONDITIONING APPARATUS

Rudolph J. Eisinger, Thornbury Township, Delaware County, Pa., assignor to Westinghouse Electric Corporation, East Pittsburgh, Pa., a corporation of Pennsylvania

Application February 14, 1942, Serial No. 430,841

7 Claims. (Cl. 62—129)

This invention relates to air conditioning apparatus, more particularly to a reversible cycle refrigerating system for either heating or cooling air for comfort, and it has for an object to provide improved apparatus of the character set forth.

Another object of the invention is to provide heat transfer from the refrigerant in the capillary tube to the suction gas during both cycles of operation and with the reversing valve disposed within the casing of the motor-compressor unit.

Another object is to provide counterflow heat transfer from the refrigerant in the capillary tubes to the suction gas during both cycles of operation.

The refrigerating system reverses the heating or cooling cycle by reversing the flow of refrigerant through the condenser and the evaporator. The reversing valve is disposed within the casing which encloses the motor compressor unit. The system includes expansion means comprising two capillary tubes which connect between the condenser and the evaporator and are in heat-transfer relation with the conduits extending between the reversing valve and the respective heat exchangers (condenser and evaporator). Check valves control the flow through the capillary tubes and are arranged so as to permit flow of refrigerant through that capillary tube which is in heat-transfer relation to the conduit containing suction gas.

These and other objects are effected by my invention as will be apparent from the following description and claims taken in connection with the accompanying drawing, forming a part of this application, in which:

Fig. 1 is a diagrammatic view of the reversible cycle refrigerating system in accordance with this invention;

Fig. 2 shows an alternate arrangement of the heat exchangers and capillary tubes; and,

Fig. 3 is a sectional view of a reversing valve which may be employed.

Referring to the drawing for a detail description of the invention, in Fig. 1 is shown a reversible cycle refrigerating system including two heat exchangers 10 and 11 which may be of the conventional cross-finned serpentine coiled type. Provision is made for conveying air over the coil 10 and delivering the same to the enclosure to be air conditioned. The coil 10 serves as the evaporator during the cooling cycle and as the condenser during the heating cycle. Provision is also made for conveying outside air over the coil 11 and discharging the same to outdoors or other place exterior of the enclosure. The coil 11 serves

as the condenser during the cooling cycle and as the evaporator during the heating cycle. The runs or tubes of each coil are preferably connected to provide a refrigerant path extending from the top through the successively lower adjacent runs to the bottom of the coil so that when the coil is serving as the condenser the condensed refrigerant flows by gravity to the bottom of the coil.

10 The refrigerating system further includes a motor compressor unit 13 which comprises a compressor 14 and a motor 15 directly connected to the compressor for driving the same. The compressor and the motor are enclosed within a hermetically-sealed or fluid-tight casing 16. The compressor draws refrigerant gas from the interior of the casing 16, the gas being drawn through the motor for the purpose of cooling the same and then conveyed through a conduit 17 to the compressor. The compressed gas is conveyed from the compressor through a discharge conduit 18 to a reversing valve 19. A reservoir or accumulator 21 is provided in the path of the suction gas to separate out and to retain liquid refrigerant from the suction gas returning from the evaporator. The accumulator 21 is disposed within the casing 16 and its inlet is connected to the reversing valve 19 by a conduit 22. Refrigerant gas is discharged from the top of the accumulator 21 directly into the interior of the casing 16 while the liquid refrigerant is retained therein. The reversing valve 19 is connected to the upper ends of the coils 10 and 11 by means of conduits 23 and 24.

15 25 30 35 40 45 50 55 The reversing valve 19 is adapted to place the compressor suction and discharge in communication with the coils 10 and 11, respectively, and to reverse the connections and place them in communication with the coils 11 and 10, respectively. While any suitable construction of reversing valve may be used so far as the present invention is concerned, it is preferred to use the one which is shown in Fig. 3 and which will be readily apparent from the drawing. This valve involves the invention of John G. Ritter, claimed in his application Serial No. 377,410, filed February 5, 1941. It includes a casing 25 made in three parts and an axially-movable valve member 26 having annular ribs or lips 27 and 28 which extend into annular recesses 29 and 30 communicating with the conduits 23 and 24, respectively. The discharge conduit 18 communicates with the interior of the casing 25 intermediate the recesses 29 and 30 while the conduit 22 communicates with the right-hand end of the interior of the casing

and also with the left-hand end through a passage formed in the valve member 26. When the valve member 26 is moved to the right so that the ribs 27 and 28 seat against the right-hand sides of the recesses 29 and 30, as shown in Fig. 3, the conduit 22 communicates with the conduit 24 and the conduit 18 communicates with the conduit 23. When the valve member 26 is moved to the left to seat the ribs 27 and 28 against the left-hand sides of the recesses, the connections are reversed, the conduit 22 communicating with the conduit 23 and the conduit 18 communicating with the conduit 24.

Suitable provision is made for actuating the reversing valve 19. In accordance with the invention of E. R. Wolfert, as disclosed in his copending application Serial No. 400,162, filed June 28, 1941, the reversing valve 19 is actuated by and in accordance with the direction of rotation of the shaft 20 of the motor compressor unit. By using a single phase compressor motor the direction of rotation may be readily reversed by connecting the compressor winding to one side or the other of the electrical supply conductors. This is illustrated in Fig. 1 wherein the double-throw switch 31 is adapted to place the circuit of the capacitor winding, which includes the capacitor 32, to either the line conductor L1 or L2. When the capacitor circuit is connected to the conductor L1, the shaft 20 rotates in counterclockwise direction, as seen in Fig. 1, and when it is connected to the conductor L2 the shaft 20 rotates in clockwise direction. A switch 33 may be provided in the line conductor L1 to interrupt the supply of current to the motor.

The mechanism for actuating the reversing valve 19 includes a sleeve 34 which encircles the shaft 20 and which is dragged by the shaft when it is free to rotate. However, it is adapted to slip relative to the shaft. When the shaft 20 rotates in counterclockwise direction, the sleeve 34 moves the movable valve member 26 to the right to the position shown in Fig. 3 to cause the refrigerating system to operate on the cooling cycle. When the shaft rotates in clockwise direction, the sleeve moves the valve member 26 to the left for the heating cycle. A screw 35 is provided to adjust the degree to which the sleeve 34 is clamped on the shaft 20 in order to adjust the degree of drag or slip.

The reversible cycle refrigerating system, which is illustrated diagrammatically, may be incorporated in any suitable form of apparatus. It is particularly suited for a self-contained air conditioning unit adapted to be mounted in the window of a room or a unit adapted to be placed in a room and connected outside with suitable ducts.

In accordance with the present invention, expansion means are provided which include two tubes 40 and 41 of considerable length and restricted bore connected between the lower ends of the two coils 10 and 11. Such tubes are commonly referred to in the art as capillary tubes. In the embodiment shown in Fig. 1, the flow of refrigerant during the cooling cycle is indicated by solid line arrows. During this cycle of operation, the tube 40 serves as the expansion means and the tube 41 is made inactive by a check valve 43 located near the end thereof that is considered the high-pressure or inlet end during the cooling cycle. The flow of refrigerant during the heating cycle is indicated by the broken line arrows. During the heating cycle the tube 41 serves as the expansion means and the tube 40 is made inactive by a check valve 44 located near

the end thereof that is considered the high-pressure or inlet end thereof during the heating cycle.

The capillary tube 40 is arranged in heat-transfer relation to the conduit 24 which is the suction line during the cooling cycle, preferably, by soldering the two together for a suitable length thereby providing a heat exchanger 45 which permits counterflow heat-transfer from the liquid refrigerant in the capillary tube 40 to the suction gas during the cooling cycle. The capillary tube 41 is arranged in heat-transfer relation to the conduit 23 which is the suction line during the heating cycle, preferably, by soldering the two together for a suitable length thereby providing a heat exchanger 46 which permits heat transfer from the liquid refrigerant in the capillary tube 41 to the suction gas during the heating cycle.

Provision is made to avoid flow of liquid refrigerant into the inactive capillary tube during both the cooling and the heating cycle, to prevent heat transfer from the hot compressed gaseous refrigerant to the liquid refrigerant, since such heat transfer is a loss of cooling effort. This is accomplished by providing an inclined or uphill portion 47 of capillary tube that extends between the lower end of the coil 10 and the portion of the capillary tube 41 that is attached to the conduit 23. This inclined tube prevents liquid refrigerant from flowing from the coil 10 into the inactive capillary tube 41 when the system is operating on the cooling cycle. Any liquid refrigerant trapped in the inactive capillary tube 41 between the check valve 43 and the coil 10 is transformed into highly superheated vapor by the heat from the hot gas in the high-pressure line 23 and this vapor is substantially static. An inclined or uphill portion 48 of capillary tube is also provided between the lower end of the coil 11 and the portion of the capillary tube 40 that is attached to the conduit 24. This inclined or uphill tube 48 prevents liquid refrigerant from flowing from the coil 11 into the inactive capillary tube 40 when the system is operating on the heating cycle. Any liquid refrigerant trapped in the inactive capillary tube 40 between the check valve 44 and the coil 11 is transformed into highly superheated vapor by the heat from the hot gas in the high-pressure line 24 and this vapor is substantially static.

In the embodiment shown in Fig. 2, check valves 43' and 44' are provided near the discharge or low-pressure ends of the capillary tubes 41' and 40', respectively. With this arrangement, the inactive portions of the capillary tubes are on the high-pressure sides of the check valves, instead of on the low-pressure sides, as with the arrangement shown in Fig. 1. An inclined or uphill portion 47' of capillary tube connects between the lower end of the coil 11 and that portion of the capillary tube 41' that is attached to the conduit 23 to prevent liquid refrigerant from flowing from the coil 11 into the inactive capillary tube when the system is operating on the cooling cycle. Likewise, an inclined or uphill portion 48' of capillary tube connects the lower end of the coil 10 to that portion of the capillary tube 40' that is attached to the conduit 24 to prevent liquid refrigerant from flowing from the coil 10 into the inactive capillary tube 40' when the system is operating on the heating cycle. In all other respects, this embodiment is the same and operates in the same manner as the previous embodiment.

It will be understood that any desired length

of capillary tube beyond the heat exchanger portion may be provided at each end; also that any desired total length of each tube may be provided.

Operation

Assume that it is desired to cool the enclosure served by the refrigerating system illustrated in Fig. 1. The switch 31 is placed in the position illustrated to provide the cooling cycle and the switch 33 is closed to connect the motor with the source of electric current. The shaft 20 rotates in counterclockwise direction moving the valve member 26 to the right, to the position illustrated in Fig. 3. The system now operates in the usual manner of a refrigerating system. Refrigerant vapor from the interior of the casing 16 is drawn through the motor and the conduit 17 to the compressor where its pressure is increased. The compressed refrigerant is conveyed through the conduit 18, the connecting passage of the reversing valve 19 and the conduit 23 to the outside air or condenser coil 11. The condensed refrigerant flows through the capillary tube 40 wherein its pressure is reduced. It then flows through the conditioned air coil or evaporator 10 wherein it extracts heat from the air which is circulated over the coil 10 and delivered to the enclosure, the refrigerant being vaporized by the extracted heat. The vaporized refrigerant then flows through the conduit 24, the connecting passage of the reversing valve 19 and the conduit 22, and the accumulator 23 to the interior of the casing 16 from which it is recirculated.

During this cycle, liquid refrigerant trapped in the inactive capillary tube 41 is transformed into highly superheated vapor, and the inclined or uphill portion 41 of the capillary tube prevents liquid refrigerant from flowing from the coil 10 into the tube 41. This absence of flow prevents heat transfer from the pressure line 23 to the liquid refrigerant.

Referring to Fig. 2, the operation during the cooling cycle is the same as that of the first embodiment except that the gaseous refrigerant in the heat-exchanger portion of the inactive capillary tube is in communication with the condenser and is therefore at high pressure. This embodiment has the advantage that, in the event of leakage through the check valve, the refrigerant leaking therethrough would be gaseous refrigerant, thereby reducing the leakage of refrigerant measured by weight.

Assume that it is desired to heat the enclosure served by the refrigerating system illustrated in Fig. 1, the switch 31 is moved to place the capacitor winding in the circuit including the line L2 and the switch 33 is closed. The shaft 29 operates in clockwise direction dragging the sleeve 34 with it until the valve member 26 is moved to the left. The connections are now reversed so that the compressed gas flows through the conduit 24 to the conditioned air coil 10. As it flows through the coil 10 it gives up its superheat and latent heat to the air circulating over the coil and is thereby condensed. The heated air is delivered to the enclosure to maintain it at a comfortable temperature. The condensed refrigerant flows through the successive tubes to the bottom of the coil 10 from which it enters the capillary tube 41, wherein its pressure is reduced. From the latter it enters the outside air coil 11. As it flows through the latter, it absorbs heat from the outside air flowing over the coil 11 and is thereby vaporized. The vaporized refrigerant discharged from the

upper end of the coil 11 flows through the conduit 23, the connecting passage of the reversing valve 19, the conduit 22 and the accumulator 23 to the interior of the casing 16. From the latter it is circulated through the motor, the conduit 17 and the compressor 14 to the discharge conduit 18.

During this cycle, liquid refrigerant trapped in the inactive capillary tube 40 is converted into highly superheated vapor, and the inclined portion of the capillary tube prevents liquid refrigerant from flowing from the coil 11 into the tube 40. This absence of flow in this tube prevents heat transfer from the high-pressure line to the liquid refrigerant.

The operation of the embodiment shown in Fig. 2 to heat the air within the enclosure is substantially the same as that for the embodiment shown in Fig. 1, except, that the gaseous refrigerant in the heat-exchanger portion of the inactive capillary tube is in communication with the condenser and is therefore at high pressure.

In both embodiments of this invention, it will be noted that when operating on both the cooling and the heating cycle, the flow of gas in the suction line is in a direction opposite to the flow of liquid refrigerant in the capillary tube attached thereto. This counterflow of gas and liquid refrigerant permits the liquid refrigerant to give up a maximum amount of heat to the suction gas. This transfer of heat from the liquid refrigerant to the suction gas increases the efficiency of the refrigerating system.

While I have shown my invention in several forms, it will be obvious to those skilled in the art that it is not so limited, but is susceptible of various other changes and modifications without departing from the spirit thereof, and I desire, therefore, that only such limitations shall be placed thereupon as are specifically set forth in the appended claims.

What I claim is:

1. In a reversible cycle refrigerating system for heating or cooling air for an enclosure, the combination of a compressor, first and second heat exchangers, the second heat exchanger being arranged to heat or cool air for the enclosure, first and second expansion devices connected between said heat exchangers and serving to expand refrigerant from condensing pressure to evaporating pressure during the cooling cycle and the heating cycle, respectively, each of said expansion devices comprising a passage of considerable length and restricted flow area, and means including valve mechanism and conduit portions for selectively connecting the suction and discharge of said compressor to said first and said second heat exchanger, respectively, for heating air for the enclosure, or to said second and said first heat exchanger, respectively, for cooling air for the enclosure, said conduit portions being constructed and arranged to convey the expanded and vaporized refrigerant in counterflow heat transfer to the refrigerant in said first expansion device during the cooling cycle and to the refrigerant in said second expansion device during the heating cycle.
2. In a reversible cycle refrigerating system for heating or cooling air for an enclosure, the combination of a compressor, first and second heat exchangers, the second heat exchanger being arranged to heat or cool air for the enclosure, first and second expansion devices connected between said heat exchangers and serving to expand refrigerant from condensing pressure to evaporating pressure during the cooling cycle and the

heating cycle, respectively, each of said expansion devices comprising a passage of considerable length and restricted flow area, first and second conduits connected to said first and second heat exchangers, respectively, means including valve means for selectively connecting the suction and discharge of said compressor to said first and second conduits, respectively, for operation of the system to heat air for the enclosure or to said second and said first conduit, respectively, for operation of the system to cool air for the enclosure, said first and second expansion devices being arranged in heat-transfer relation to said second and said first conduits, respectively, for a considerable length thereof in such manner that during the cooling cycle the liquid refrigerant in said first expansion device flows in counterflow heat relation to the gaseous refrigerant in said second conduit and during the heating cycle the liquid refrigerant in said second expansion device flows in counterflow heat relation to the gaseous refrigerant in said first conduit.

3. In a reversible cycle refrigerating system for heating or cooling air for an enclosure, the combination of a compressor, first and second heat exchangers, first and second conduits connected to said compressor and to said first and second heat exchangers, respectively, said second heat exchanger being arranged to heat or cool air for the enclosure, first and second capillary tubes connected in parallel between said heat exchangers and serving to expand refrigerant from condensing pressure to evaporating pressure during the cooling cycle and the heating cycle, respectively, a check valve arranged in each of said capillary tubes, said check valves being arranged so that during the cooling cycle said second capillary tube is made inactive by its check valve and during the heating cycle said first capillary tube is made inactive by its check valve, and valve means for selectively connecting the suction and discharge of said compressor to said first and said second conduits, respectively, for operation of the system to heat air for the enclosure or to said second and said first conduits, respectively, for operation of the system to cool air for the enclosure.

4. In a reversible cycle refrigerating system for heating or cooling air for an enclosure, the combination of a compressor, first and second heat exchangers, first and second conduits connected to said compressor and to said first and second heat exchangers, respectively, the second heat exchanger being arranged to heat or cool air for the enclosure, first and second capillary tubes connected between said heat exchangers, said first capillary tube being arranged in heat-transfer relation to said second conduit for a considerable length thereof and adapted to expand refrigerant from condensing pressure to evaporating pressure during the cooling cycle, said second capillary tube being arranged in heat-transfer relation to said first conduit for a considerable length thereof and adapted to expand refrigerant from condensing pressure to evaporating pressure during the heating cycle, means for rendering said second capillary tube inactive and maintaining absence of flow thereto during the cooling cycle, means for rendering said first capillary tube inactive and maintaining absence of flow thereto during the heating cycle, and valve means for selectively connecting the suction and discharge of said compressor to said first and said second conduits, respectively, for operation of the

system to heat the air for the enclosure or to said second and said first heat exchanger, respectively, for operation of the system to cool the air for the enclosure.

5. In a reversible cycle refrigerating system for heating or cooling air for an enclosure, the combination of a compressor, first and second heat exchangers, first and second conduits connecting said compressor to said heat exchangers, the second heat exchanger being arranged to heat or cool air for the enclosure, first and second capillary tubes connected between said heat exchangers, said first and second capillary tubes being arranged for a considerable length thereof in heat-transfer relation to said second and said first conduits, respectively, said first capillary tube serving to expand refrigerant from condensing pressure to evaporating pressure during the cooling cycle, a check valve arranged in said second capillary tube to render the same inactive during the cooling cycle, that portion of said second capillary tube that is in heat-transfer relation to said first conduit being on the low pressure side of said check valve during the cooling cycle, said first conduit being the high-pressure conduit during this cycle of operation, the heat from the refrigerant gas flowing through said first conduit serving to transform liquid refrigerant trapped in said second capillary tube into superheated gas some of which remains static in said second capillary tube, said second capillary tube serving to expand refrigerant from condensing pressure to evaporating pressure during the heating cycle, a check valve arranged in said first capillary tube to render the same inactive during this cycle of operation, that portion of said first capillary tube that is in heat-transfer relation to said second conduit being on the low pressure side of said check valve during the heating cycle, said second conduit being the high pressure conduit during the heating cycle, the heat from the refrigerant gas flowing in said second conduit being such that it transforms liquid refrigerant trapped in the first capillary tube into superheated vapor some of which remains static in this tube, and valve means for selectively connecting the suction and discharge of said compressor to said first and said second conduits, respectively, for operation of the system to heat air for the enclosure or to said second and said first conduits, respectively, for operation of the system to cool air for the enclosure.

6. In a reversible cycle refrigerating system for heating or cooling air for an enclosure, the combination of a compressor, first and second heat exchangers, first and second conduits connecting said compressor to said heat exchangers, the second heat exchanger being arranged to heat or cool air for the enclosure, first and second capillary tubes connected between said heat exchangers and serving to expand liquid refrigerant from condensing pressure to evaporating pressure during the cooling cycle and the heating cycle, respectively, said first and second capillary tubes being arranged for a considerable length thereof in heat-transfer relationship to said second and said first conduits, respectively, a check valve arranged in said second capillary tube to render the same inactive during the cooling cycle, said check valve being so positioned that the portion of said second capillary tube that is in heat-transfer relation to said first conduit is on the high-pressure side of said check valve during the cooling cycle, a check valve arranged in said first capillary tube to render the same inactive during the heating

cycle, said check valve being so positioned that the portion of the first capillary tube that is in heat-transfer relation to said second conduit is on the high-pressure side of said check valve during the heating cycle, and valve means for selectively connecting the suction and discharge of said compressor to said first and said second conduits, respectively, for operation of the system to heat air for the enclosure or to said second and said first conduits, respectively, for operation of the system to cool air for the enclosure.

7. In a reversible cycle refrigerating system for heating or cooling air for an enclosure, the combination of a compressor, first and second heat exchangers, the second heat exchanger being arranged to heat or cool air for the enclosure, first and second capillary tubes connected between said heat exchangers and serving to expand refrigerant from condensing pressure to evaporating pressure during the cooling cycle and

the heating cycle, respectively, check valves arranged to render the second capillary tube inactive during the cooling cycle and the first capillary tube inactive during the heating cycle, means including an inclined portion of capillary tube to prevent liquid refrigerant from flowing from said second heat exchanger into said second capillary tube during the cooling cycle, means including an inclined portion of capillary tube to prevent liquid refrigerant from flowing from said first heat exchanger into said first capillary tube during the heating cycle, and valve means for selectively connecting the suction and discharge of said compressor to said first and said second heat exchangers, respectively, for heating air for the enclosure or to said second and said first conduit, respectively, for cooling air for the enclosure.

RUDOLPH J. EISINGER.
